UNITED STATES PATENT OFFICE.

WILLIAM MARR WARD, OF GRAND BLANC, MICHIGAN.

CARRIAGE-TOP.

SPECIFICATION forming part of Letters Patent No. 372,949, dated November 8, 1887.

Application filed July 11, 1887. Serial No. 244,003. (No model.)

To all whom it may concern:

Be it known that I, WILLIAM MARR WARD, a citizen of the United States, and a resident of Grand Blanc, in the county of Genesee and State 5 of Michigan, have invented certain new and useful Improvements in Devices for Raising and Lowering Carriage-Tops; and I do hereby declare that the following is a full, clear, and exact description of the invention, which will 10 enable others skilled in the art to which it appertains to make and use the same, reference being had to the accompanying drawings, and to the letters of reference marked thereon, which form part of this specification.

15 My invention relates to a device for raising and lowering carriage-tops, and has for its object to provide means by which the top can be raised or lowered by the occupant of the carriage without great manual effort or necessitating the uncomfortable position required in the ordinary construction in reaching out of the carriage and at some distance back of the front bows at each side in accomplishing this end. I attain these objects by 20 means of a lever located within easy reach of the occupant, said lever being connected to the carriage-top braces by intermediate connections secured firmly to the braces, thereby obviating all necessity of the attachments sliding 25 upon the braces or of so loose connection as to permit of rattling at this point. I have also arranged for constructing my improvement integral with the top or attachable to those already constructed.

30 The invention also consists of various parts and details, hereinafter more fully set forth and described.

Reference is to be had to the accompanying drawings, forming part of this specification, 40 in which similar letters of reference indicate corresponding parts in all the figures.

Figure 1 is a perspective view of a carriage-top provided with my attachments. Fig. 2 is a detail view of a hanger employed in attaching my improvements to the carriage. Fig. 5 is a similar view of a modified form of hanger. Fig. 3 is a detail view of a clasp for attaching the jointed arms to the carriage-braces. Fig. 4 is a plan view in cross-section 45 on lines α α , Fig. 1, showing the clasp in position upon the brace, the arm being pivoted

therein. Fig. 6 is a perspective view of a carriage-top with my improvements attached, showing in dotted lines the movement of the jointed arms when in the act of lowering or 55 raising the top. In this view the rocking bar is journaled in bearings formed integral with the top as shown in the detail view, Fig. 7, the jointed arms being attached to the carriage-braces by being journaled upon studs 60 formed upon the carriage-braces, as shown in the detail view in Fig. 8. Fig. 9 is a detail view of a clasp provided with a stud, and showing the arm pivoted thereon.

A is the carriage-seat; B, the top, having 65 jointed braces C—one on each side—and side rails, D. These parts, being of the usual construction, need no further description.

E, Fig. 2, is a two-part hanger, adapted to fit upon and embrace the side rail, D, one being attached to each rail, and having a projecting end of sufficient length to reach beyond the studs D', upon which the braces C are journaled. The projecting end of this hanger has a perforation, G, into which the rocking bar 70 H is journaled. In Fig. 5 this hanger is shown as formed with a projection, E', adapted to fit over stud D', for the purpose of giving rigidity to the same. Upon the ends of rocking bar 75 H are fastened jointed arms K, preferably by squaring the ends of said bar and slipping the end of arm K (which has a square perforation) 80 upon the same, and securing the arm from longitudinal displacement by any preferred means, thereby securing rotation of the arm 85 corresponding with the rotation of the bar. Arms K are formed with a rule-joint intermediate their lengths, and are firmly secured to the carriage-braces by any means that will 90 prevent their longitudinal movement or rattling. As shown in Fig. 1, this is accomplished by means of clasps L. (Shown in detail in Fig. 3 and in horizontal cross-section in Fig. 4.)

These clasps are formed of two parts, each part being hollowed out to conform to the size and 95 shape of the carriage-braces, and are perforated at their projecting ends at O and P for the insertion of bolts O' and P', respectively, the rear sides of the clasps having ledges O'', to form spaces, into which are pivoted the upper ends of arms K, and allow the clasps to be 100 rigidly secured to the braces without imping-

ing upon said arms to prevent their pivotal action. If desired, these clasps may be formed of a single piece embracing the brace, as indicated by dotted lines in Fig. 4, or be formed 5 with a stud, C', upon which arm K is pivoted and held in place by nut C'', as shown in Fig. 9.

In Fig. 6 is shown a form of attachment 10 adaptable to carriages formed with a view of using my improvements, in which I form a stud, C', either integral with or separate from the brace C, and slip the perforated end of the jointed arm thereon, it being held to place by nut C''. I have also shown in this figure the side rails, D, extending past the stud E', and 15 having perforations into which the rocking bar is journaled. This construction is shown more fully in Fig. 7.

J is a hand-lever attached to the rocking bar in a convenient position at the side of the seat 20 within easy reach of the occupant of the carriage.

The operation is as follows: When it is desired to lower the carriage-top, the occupant 25 grasps the lever J, which lies in a horizontal position at the side of the seat, and raises the same to a vertical position. This causes jointed arms K to break joints, thereby pulling upon braces C with a similar effect, and the top is easily lowered. The initial movement is shown in 30 dotted lines, Fig. 6, as indicated at J' and K'. When it is desired to raise the top, the operation is reversed. It will be observed that with 35 this construction there is no sliding of the clasps upon the braces, with their tendency to abrasion of the covering of the same, and also that I am enabled to connect the jointed arms with the braces in such manner as to avoid rattling at their point of attachment.

I am aware that numerous forms of attachments for connecting the rocking bar with the 40 top or seat, as well as of connecting the jointed arms to the carriage-braces, can be employed without departing from the spirit of my invention; hence I wish the present illustrations 45 to be regarded as simply diagrammatic of some of the preferred forms that may be employed.

Having described my invention, what I claim, and desire to secure by Letters Patent, is—

1. In a device for raising and lowering carriage-tops, a rocking bar journaled back of the pivotal attachment of the carriage-braces, a hand-lever connected with the rocking bar and extending forward of the same in parallel relation with the side braces, and jointed arms 55 attached to the rocking bar and extending vertically with and pivotally attached to the carriage-braces, as and for the purpose set forth.

2. A device for raising and lowering carriage-tops, consisting of a rocking bar journaled back of the carriage-seat, a hand-lever attached thereto and extending parallel with the side braces and at one end of the seat, and arms having a rule-joint attached to the rocking bar and extending upwardly to and connected 60 with the carriage-braces by being journaled on studs removably attached thereto, as and for the purpose set forth.

In testimony that I claim the foregoing as my own I hereby affix my signature in presence of 70 two witnesses.

WILLIAM MARR WARD.
